UNITED STATES PATENT OFFICE.

KARL MAX ADLER, OF PAUNSDORF, NEAR LEIPZIG, GERMANY, ASSIGNOR TO EMIL KAHLE, OF PAUNSDORF, NEAR LEIPZIG, GERMANY, A CORPORATION OF GERMANY.

PLATEN PRESS.

1,413,699.

Specification of Letters Patent. Patented Apr. 25, 1922.

Application filed September 1, 1920. Serial No. 407,549.

(GRANTED UNDER THE PROVISIONS OF THE ACT OF MARCH 3, 1921, 41 STAT. L., 1313.)

To all whom it may concern:

Be it known that I, KARL MAX ADLER, engineer, a citizen of Germany, residing at Paunsdorf, near Leipzig, Germany, have invented certain new and useful Improvement in Platen Presses, (for which I have filed application in Germany on Oct. 18, 1913; Switzerland on Feb. 11, 1914, patented to Emil Kahle #66,745; Austria on Feb. 12, 1914; Belgium on Feb. 17, 1914; France on Feb. 17, 1914; Italy on Feb. 27, 1914; Great Britain Feb. 16, 1914, Patent #4022 of 1914,) of which the following is a specification.

15 My invention refers to platen presses having a substantially vertical bed i. e., a vertical or nearly vertical bed, and more especially to a novel device for automatically removing printed sheets from such a press, 20 its particular object being to provide a device of this class which is distinguished both by its simplicity and efficiency of action.

Up till now two different methods of automatically removing the work or printed 25 sheets from a platen press are known, namely by striking the sheet laterally and by blowing it laterally. The scope of these methods is limited, both as regards the size and thickness of the work. Lateral striking is insufficient to remove the sheet from 30 large platens, and with thin paper there is the danger that the sheet instead of being completely removed from the platen, is only displaced thereon. If however, the member 35 for removing the work is guided or moved over the whole platen, there is the disadvantage that an injury to the raising device is almost unavoidable and, moreover, thin paper is apt to be merely displaced instead 40 of being entirely removed. These disadvantages are avoided in one arrangement by which the work is laterally engaged by grippers carried by a link parallelogram and drawn right across the platen and then released. This arrangement, which, as it is 45 driven from the main shaft, is only applicable to platen printing presses operated by foot or power, has in addition to its cost the defect that the work can only be gripped after the platen has completed its return 50 movement and come to rest in the open position, which causes a loss in time.

The object of the present invention is to avoid the above mentioned defects of the

known removing devices while retaining 55 their advantages, and by means which are simple in construction and correspondingly cheap.

According to the present invention the sheet is gripped laterally immediately after 60 the printing, that is to say while the platen is opening—drawn off the platen, and out of the machine and then delivered to one side so that the platen as soon as it comes to rest, is free for the reception of the next 65 sheet.

The device can operate efficiently irrespective of the size or thickness of the sheet.

The gripping device may take the form 70 of mechanical grippers adapted to oscillate or reciprocate and to close on to the sheet as they complete their inward stroke, and to open to release the withdrawn sheet when they reach the end of their outward stroke; or it may take the form of a suction device 75 adapted to engage with the sheet, withdraw it from the platen and then, owing to the disconnection of the suction action, release the sheet for delivery.

The gripping device is guided by guiding 80 means carried by the platen or adjacent oscillating part of the machine so as to follow the movements thereof.

The guiding means may be in the form 85 of a rail or iron bar of round or angular section forming a lateral extension of the platen, or the gripping device may be carried by a bar which slides in suitable guides below the platen.

One mode of carrying out the invention is 90 illustrated by way of example in the accompanying drawings, according to which the gripping device is in the form of a pair of mechanical grippers adapted to slide on a guide rail extending laterally from the 95 platen of a socalled Boston press.

Fig. 1 being an elevation of the press with some parts broken away and

Fig. 2 a plan.

Figs. 3, 4 and 5 are respectively an elevation, 100 a cross section and a plan of my improved gripping device on a larger scale.

In the example illustrated, B is the bed and b is the platen carried by the usual knee-shaped member a. A rail c extends 105 from the right hand side of the platen as seen from the operator's position. A plate d, fitted with a pair of grippers i is posi-

tively guided on the rail *c* and is moved outwardly thereon by the hand lever *g* through the medium of a wire cable *k* which is attached to a lug *g'* on the hand lever, passes 5 around a guide pulley *f* thence between the knee member *a* around a second pulley *e* on the outer end of the rail *c*, and is secured to the plate *d*. The plate *d* is moved inwardly on the rail by a spring *s*. The platen is of 10 known construction where the rail is secured to it so that the sheet lies free on the edge and can be gripped by the grippers *i*, which then withdraw it as they are moved outwardly on the rail by the cable *k* and hand 15 lever *g* as the platen moves open.

The grippers *i* are closed and opened automatically just as they complete their inward and outward strokes respectively, by means of a sliding wedge *l* which strikes 20 against stops *o* and *m*, and accordingly releases or raises a pin *n* riveted to the upper gripper blade. Therefore when the grippers *i* have completely withdrawn a sheet and are opened by the wedge *l* striking the 25 stop *m*, they release the sheet which falls by gravity into a box provided to receive it. A fresh sheet is then placed in position, then as the platen begins to close, the grippers move inwardly still open until they are 30 released by the wedge *l* striking the inner stop *o* whereupon they close on the edge of the sheet and are ready to withdraw it as soon as the platen again starts to move open.

In order to prevent the withdrawn sheet 35 being soiled by the lubricant on the rail *c* it is adapted to be drawn without appreciable friction along guard wires or strips *p* conveniently stretched between and held by the stops *o* and *m* at a suitable distance from 40 the rail, the plate *d* being suitably grooved to clear them in its reciprocation.

As shown in Figures 3, 4, and 5, a wiper *q* conveniently formed of flat iron bent to

the shape shown and secured to the end of the rail *c* is provided with adjustable stops 45 *r* against which the released sheet strikes and is prevented from moving further outward, thus ensuring that it shall be positively thrown aside as well as under its own momentum. 50

I claim:

1. In a printing press, the combination with a substantially vertical bed, of an oscillating platen cooperating with said bed, guiding means carried by said platen and a sheet gripping device reciprocable on said guiding means. 55

2. In a printing press, a substantially vertical bed, a platen oscillatable into and out of impression relation to said bed, guiding 60 means carried by said platen, and a sheet gripping device reciprocable on said guiding means and towards and away from the vertical edge of said platen.

3. In a printing press, the combination 65 with a vertical bed, of an oscillating platen cooperating with said bed, guides carried by said platen, and a sheet gripping device reciprocable on said guides in a vertical plane into and out of position to grip a sheet 70 which has received an impression between said platen and bed for retracting said sheet.

4. In a printing press, the combination 75 with a vertical bed, of an oscillatable platen cooperating therewith, guides carried by said platen, sheet gripping means reciprocable on said guides into and out of position to grip the sheet for retracting said sheet from between said bed and platen, and stops for arresting the movement of said 80 sheet to permit it to drop by gravity in a direction transverse to the direction of its retraction.

In testimony whereof I have hereunto set my hand.

KARL MAX ADLER.
